FIG. 1 is a front perspective view of a combined coffee urn and stand therefor embodying my new design;

FIG. 2 is a front elevational view;

FIG. 3 is a side elevational view thereof;

FIG. 4 is a top plan view thereof;

FIG. 5 is a bottom plan view thereof;

FIG. 6 is an elevational view, partly in section, of the cover member; and

FIG. 7 is a partial rear elevational view.

My design is characterized by the combination on an urn of the form shown of the specific forms of side handles and cover knob having concave curves on their outer edges coordinate with the concave curvature of the cut-out portion of the base having the specific form shown.

I claim:

The ornamental design for a combined coffee urn and stand therefor, as shown and described.
